UNITED STATES PATENT OFFICE.

FREDERICK MAX PORITZ, OF NEW YORK, N. Y., ASSIGNOR TO STAR CHANDELIER COMPANY, INC., OF NEW YORK, N. Y., A CORPORATION OF NEW YORK.

DESIGN FOR A CHANDELIER BODY.

Application filed October 12, 1923. Serial No. 7,476. Term of patent 3½ years.

To all whom it may concern:

Be it known that I, FREDERICK MAX PORITZ, a citizen of Germany, residing at New York, in the county of New York and State of New York, have invented a new, original, and ornamental Design for a Chandelier Body, of which the following is a specification, reference being had to the accompanying drawing, forming part thereof.

Figure 1 is a plan view of a chandelier body, showing my new design.

Figure 2 is a side view of a chandelier body, showing my new design.

I claim:

The ornamental design for a chandelier body, as shown.

FREDERICK MAX PORITZ.
